Primary Examiner — Susan E Krakower(74) *Attorney, Agent, or Firm* — Kenneth A. Roddy(57) **CLAIM**

The ornamental design for an adhesive plantar fascia support, as shown and described.

DESCRIPTION

FIG. 1 is a top perspective view of an adhesive plantar fascia support showing my new design from the top, bottom edge, and right-hand side;

FIG. 2 is a top plan view thereof; and,

FIG. 3 is a bottom plan view thereof.

It is understood that the adhesive plantar fascia support shows no appreciable thickness.
